UNITED STATES PATENT OFFICE.

JOHN C. LEE, OF BROOKLINE, MASSACHUSETTS.

PREPARATION OF GRANULAR CARBON.

1,071,442.

Specification of Letters Patent. Patented Aug. 26, 1913.

Application filed March 29, 1913. Serial No. 757,558.

To all whom it may concern:

Be it known that I, JOHN C. LEE, a citizen of the United States, residing at Brookline, in the county of Norfolk and State of Massachusetts, have invented new and useful Improvements in the Preparation of Granular Carbon, of which the following is a specification.

My invention is a process for preparing 10 a granular carbon of a uniform predetermined electrical resistance for use in microphonic telephone transmitters and an apparatus suitable to be used in performing the process.

Granular carbon is used in the manufacture of microphonic telephone transmitters and is generally made by heating finely divided anthracite coal or some prepared substitute until it possesses the desired electrical resistance. As heretofore 20 produced such particles of granular carbon have been of unequal electrical resistance due to the fact that in the heating process it was impossible to subject each of 25 the particles to substantially the same degree of heat for substantially the same length of time and as no means was known for separating the particles into groups after the roasting, each possessing substantially 30 the same degree of electrical resistance, the result was not satisfactory. Heretofore, the heating or roasting process has been applied to the granular carbon contained in some receptacle, the heat being applied from without, in consequence of which 35 those particles in contact with the container and nearest to the heat receive more heat than those more distant, toward the center of the mass, and agitation of the mass did not serve to give to each particle, with certainty, its proper amount of heat for the proper length of time.

To secure a uniform product, which is essential for the best results, the important 40 factors which must be controlled are, first, the intensity of the heat; second, the time during which the heat is applied; and, third, the equal heating for an equal time of each particle.

My process consists in heating the finely

divided anthracite coal or other suitable material by means of an electrical current of definite intensity, passing through the body of material itself and, at the same time, controlling the particles of the body 55 of material, so that each particle is exposed to the current for a definite time.

In the drawings I have shown apparatus suitable for performing my process.

Figure 1 is a plan and Fig. 2 a sectional elevation on line 2—2 of Fig. 1, of a simple form of apparatus; Fig. 3 is a plan; Fig. 4 a side elevation and Fig. 5 a sectional elevation on line 3—3 of Fig. 3; Figs. 3, 4 and 5 show a specifically different form, from that 65 shown in Figs. 1 and 2.

In the drawings two forms of roasting apparatus are shown for performing the process, that shown in Figs. 1 and 2 being a very simple structure while that shown in 70 Figs. 3, 4 and 5, has more detailed provision for adjustment and regulation, whereby different materials may be treated and the result varied by the use of the adjusting means. The device shown in Figs. 1 and 2 75 consists of a chamber or shell, 1, open at the top and bottom and made of plumbago or some other suitable electrical conductor. This conductor shell is mounted upon an annular throat, 2, of refractory material, 80 such as fire-brick, the aperture in which is relatively narrow as compared with the diameter of the interior of the upper shell, 1. This annulus, 2, of refractory material, is intended to be replaced when desired to 85 give throats or passages of different diameters and capacity. Beneath the fire brick annulus or throat a second ring, 3, of plumbago or other suitable electrical conductor is secured. The conductors 1 and 3 are connected by suitable wires, *h*, to a suitable source of electrical energy *g*.

The device shown in Figs. 3, 4 and 5 is made up of a vessel made of refractory material such as fire-clay, divided into an upper chamber *a* and a lower chamber *b*, the upper and lower chambers being connected by a narrow throat *c*. The upper chamber *a* is open at the top to allow the introduction of the material, *M*, to be treated and 95 100

the escape of gases generated by the partial decomposition of the granular carbon in the process of treatment and the lower chamber, *b*, is provided with an opening *d* controlled by a gate *e* for drawing off the roasted or prepared carbon *M'*. Inserted in the upper and lower chambers and suitably sustained are a pair of electrodes *f*, *f'*, preferably made of carbon, each connected to a suitable source of electrical energy *g* by wires *h*. As shown in the drawing the electrodes are in line with each other and with the throat *c*. If desired a gas cock *i* may also be connected with the lower chamber so that under certain conditions the roasting or treatment of the granular material can be conducted in an atmosphere of gas, introduced through the gas cock.

In using the apparatus shown in Figs. 3, 20 4 and 5 the material to be treated is placed in the chamber, *a*, and passes into the throat *c* and the lower chamber *b* by gravity, in the same manner that sand in an hour-glass goes from one chamber to the other. Electrical energy of a predetermined electromotive force being transmitted to one of the electrodes, *f*, *f'*, a current is caused to pass between the electrodes through the body of material *M* filling the throat *c* and equally heating all the particles of granular carbon within the throat. The gases of decomposition rise through the granular carbon in the chamber above and escape through the open top of the chamber.

35 By well known physical laws the amount of heat developed in this electrical furnace at *c* will depend upon the electrical resistance of the granular material and the amount of current it conducts. It will, therefore, be evident, that by controlling the current from the generating source the heat generated at *c* can be controlled.

The duration of the heating process as applied to each particle of material is governed by the time taken by each particle in passing through the contracted opening *c* from chamber *a* to chamber *b* and this may be controlled by regulating the general flow of material through the apparatus by means 45 of the gate *e* controlling the lower opening *d* of chamber *b*. In this manner it will be seen that the column of granular material in the throat *c* is reached throughout its entire cross section as it passes through the 50 throat and it is subjected to the heat, which is controlled from the generator, for the desired length of time, by regulating the speed at which the granular material flows downward under the action of gravity. As the 55 material enters the throat in its raw or untreated condition it gives the maximum resistance to the flow of the electrical current and as it passes out at the bottom, beyond the reach of the current, it gives the pre- 60 determined resistance according to the ex-

tent to which the volatile matter has been driven off and as each particle in the column of material in the throat is subjected to substantially the same amount of heat for substantially the same amount of time it follows that the result must be a substantially uniform action on each particle. It is desirable of course that the finely comminuted material should be screened before being placed in the apparatus and that particles of a relatively uniform size should be treated together.

In using the apparatus shown in Figs. 1 and 2 the material *M* to be treated is placed in the chamber *a* and passes, by gravity, through the throat *c* of the fire-brick section 2 and is discharged at the bottom through the center of the lower conductor section 3, it being understood of course that in performing the process the conducting sections 1 and 3 are connected by suitable wires *h* with the source of electrical energy *g* and that the current flows between the two electrodes 1 and 3 through the throat of the fire-brick section, 2, to heat the descending material *M*, as in the device shown in Figs. 3, 4 and 5. The control of the flow of material may be attained by changing the section, 2, and substituting one having a larger or smaller throat, as desired, or other means of control may be supplied. The roasted material is received below, in any suitable receptacle and is cooled as it falls through the air, into the same.

My preferred form is that shown in Figs. 3, 4 and 5 in which the control is at the exit of the lower chamber, the throat or exit there being governed by a suitable gate and having the same effect as controlling the passage of the material at the throat *c*.

I claim:

1. An apparatus for preparing granular carbon, consisting of a chamber; a relatively narrow throat leading from the lower part of said chamber; means to cause an electrical current, when the apparatus is in operation, to pass through the material only while in said throat, whereby the granular carbon may be exposed to the electrical current for a predetermined space of time while passing from the chamber.

2. An apparatus for preparing granular carbon, consisting of an upper and a lower chamber; a relatively narrow throat connecting said chambers; means to cause an electrical current to pass through the material in said throat, when in operation; an exit for the prepared carbon at the lower part of the lower chamber, whereby the exit of the prepared carbon therefrom may be controlled to control the movement of carbon particles through the throat in the path of the electrical current.

3. An apparatus for preparing granular carbon, consisting of an upper and a lower

chamber; a relatively narrow throat connecting said chambers; an electrode in each chamber, each adapted to be connected to an electrical source; an exit opening for the 5 prepared carbon, at the lower part of the chamber, a gate to control said opening, whereby the exit of the prepared carbon therefrom may be controlled to control the

movement of carbon particles through the throat and the electrical current. ¹⁰
Signed by me at Boston, Mass., this 27th day of March, 1913.
